U.S. 1622

Garrettson Smith & Henry Brown of Philadelphia, Pa.

Assignors to

Coce. Whiteman and Coce, of same place.

Letters Patent, No 1622, dated Aug. 5, 1862.

The schedule referred to in these Letters Patent and making part of the same.

To all whom it may concern:

By it is known that we, Garrettson Smith and Henry Brown of Philadelphia, County of Philadelphia State of Pennsylvania, have invented or produced a new and original design for the plates of a Cook Stove, termed the Monitor; and we do hereby declare the accompanying drawing with the following explanation of the same to form a full, clear and exact description of the said Design.

Fig. 1. of the drawing is a view of one of the side plates of the stove.

Fig. 2, the upper front plate.

Fig. 3, the lower front plate.

Fig. 4, the rear plate, and

Fig. 5, a view of the leg of the stove.

The side plate Fig. 1. is edged with a plain moulding, and has a large oven door and a small door.

Des. 16 22

On the edges of the large door is a plain bead or moulding, and on the face of the door is an ornament consisting of an oval figure formed by ribbed and plain beads, with foliated scrolls, and a central oval boss with radial ribs and other ornaments shown.

The small door is edged with a plain bead or moulding and has an oval ornament of a character somewhat similar to that of the ornament on the larger door.

The upper front plate Fig. 2, has its vertical edges ornamented as shown, and has a panel with an oval foliated ornament somewhat similar to that on the large door of the plate Fig. 1.

The lower front plate has on its vertical edges a ribbed moulding, and has two upper doors and two lower doors with the ornaments shown, which are of a character approximating to that of the ornaments on the small door of the side plate Fig. 1.

The rear plate Fig. 4, has three panels, each containing the oval foliated ornaments illustrated.

The leg with its ornamentations are illustrated in Fig. 5.

We claim the ornamental figures and forms represented in and by the accompanying drawing, and forming together an ornamental design for the plates of a cooking stove.

In testimony whereof we have signed our names to this specification in the presence of two subscribing witnesses.
